UNITED STATES PATENT OFFICE.

GEORGE J. STAGE, OF ROCHESTER, NEW YORK.

PHOTOGRAPHIC DEVELOPING APPARATUS.

SPECIFICATION forming part of Letters Patent No. 729,003, dated May 26, 1903.

Application filed January 31, 1903. Serial No. 141,304. (No model.)

To all whom it may concern:

Be it known that I, GEORGE J. STAGE, a citizen of the United States, and a resident of Rochester, in the county of Monroe and State 5 of New York, have invented certain new and useful Improvements in Photographic Developing Apparatus, of which the following is a specification.

This invention relates to photographic developing apparatus; and its object is to provide means whereby plates and films in sheets 10 may be developed in daylight.

In the drawings, Figure 1 is a perspective view of the developing apparatus. Fig. 2 is 15 a cross-section on the line 2 2 of Fig. 1. Fig. 3 is a top view of a frame adapted to transfer the plate or film from the plate-holder to the developing - box in position upon the plate-holder. Fig. 4 is a cross-section on the 20 line 4 4 of Fig. 3, and Fig. 5 is a top view of the developing-box and reservoir.

In the drawings, A represents a developing-box of suitable size and proportions to contain the photographic plate or film-sheet 25 that is to be developed and a sufficient quantity of the developing fluid. Adjoining the developing-box proper there is a reservoir A', adapted to hold the developing fluid and from which it is introduced into the developing- 30 box A through a channel provided for that purpose after the plate or film has been placed within said box. The reservoir A' is represented in the drawings as constituting part of the structure of the developing-box A and as 35 separated from said developing-box proper by a partition A². (See Fig. 2.) The connection between said reservoir A' and said developing- box A is represented in the drawings as consisting of a narrow slit a beneath the partition A². The slit a is preferably made so 40 narrow that the fluid will not pass freely through it until the reservoir and box are tilted, and accordingly very little of the fluid will pass from the reservoir to the developing-box A before the operator is ready to develop the plate.

The developing fluid is introduced into the reservoir A' through any suitable opening therein, and means are provided for shielding 45 said developer from light when in the reservoir. In the drawings the reservoir A' is represented as open at the top for this pur-

pose, and a series of shields a' a² a³ a⁴ are shown, which project out into said reservoir from its side walls on either side alternately, 55 so that each shield overlies the one next beneath it. In this way a circuitous channel is formed leading into the reservoir from its open top through which light cannot penetrate to the fluid. The shields may be so constructed that opposing surfaces will have an angle with the parallel sides of the reservoir and will be parallel with each other, as illustrated by the shields a² a³, Fig. 2, so that a circuitous passage of uniform size will be 60 formed between such shields.

Vertical guides a⁵ are shown in the developing-box A for directing the plate X to its position on the bottom of said box and retaining it there, and a catch a⁶ is also adapted to retain 70 said plate in position when the box is tilted. As the plate X is dropped into the developing-box A its weight is sufficient to force back the catch a⁶, so that said plate falls beneath the foot a⁷ of said catch. 75

The frame B is employed to transfer the plate from the plate-holder C to the developing-box. By means of this frame the plate can be taken from the plate-holder, that is so constructed that a plate or film can only be 80 removed from it sensitized face foremost and placed in the developing-box with the sensitized face uppermost, in which position the developing fluid can wash evenly and thoroughly over the face of the plate and the 85 process of developing can be observed. In most other developing apparatus that has been made heretofore for developing plates and films in daylight the sensitized plate is placed in the developing-box with the sensitized face down, and in that position it cannot be properly treated with the developing fluid nor can the process of developing be observed by the operator.

The frame B is adapted for use with any 95 plate-holder that is so constructed that the plate can be transferred from it into said frame without exposing it to the light. In Fig. 4 the frame B is represented as used in connection with a plate-holder C, adapted to 100 contain two plates or films, from which the plates or films can be dropped into said frame B through the side of the plate-holder when the slide in front of the plate or film has been

withdrawn. The general form of the plate-holder is represented in dotted lines in said Fig. 4; but its construction is not shown in detail.

5 The frame B is shown in the drawings as open on one side and as of suitable size and proportions to contain the plate or film. The opening on the side is large enough to permit the plate or film to pass through it. A slide

10 B' is adapted to close the open side of the frame B in the usual manner, and another similar slide B² on the other side of the frame uncovers when withdrawn a ruby or other non-actinic glass B³, through which the process of developing the plate can be observed. A septum B⁴ divides the frame B centrally and has a hole B⁵ through its center (represented in Fig. 1) for inspecting the plate or film in the developing-box A.

15 20 The frame B is rabbeted or otherwise formed on one and the same side to fit light-tight both the plate-holder that contains the plate or film and the top of the developing-box A.

25 A plate or film is transferred from the plate-holder to the developing-box through the intermediation of the frame B in the following manner: The frame B is placed beneath the plate-holder so that the rabbeted sides engage, as shown in Figs. 3 and 4. The two are 30 locked together by suitable catches. (Not shown.) The slide B' is then withdrawn from the frame B and the plate or film is dropped through the side of the plate-holder into said frame B. Next the slide B' is replaced in the 35 frame B, so as to close that side of the frame and protect the plate or film from light, and said frame is removed from the plate-holder C and placed on top of the developing-box A in the position shown in Fig. 2. In this lat-

40 45 position the same side of the frame B that engaged with the plate-holder C is in contact with the top of the developing-box. The frame B is locked to the box A, as by the catches A⁴. The plate x now occupies a position in the frame B corresponding with that shown by the dotted lines x' in Fig. 2. If the slide B' is withdrawn from the frame B, the plate will drop, sensitized face uppermost, from said frame into the developing-box A

50 55 between the guides a⁵ and beneath the foot a⁷ of the spring a⁶. The frame B excludes the light from said developing-box A, and the developing fluid having been inserted in the reservoir A' in the manner described above it

60 65 can be introduced into the developing-box A by tilting the frame until the fluid runs out of the reservoir A' through the opening a' into the developing-box A. Then by rocking the developing-box A the fluid is caused to flow back and forth over the plate. If the slide B² is removed, the process of developing can be observed through the hole B⁵ in the septum B⁴ and the ruby glass B³.

When the plate has been developed, the developing fluid is removed from said developing-box A without removing the frame B from it by tilting said box until the fluid passes

back through the passage a into the reservoir A' and then out from the said reservoir over its upper edge. It will be observed that the side A³ of the reservoir is lower than the sides of the developing-box A. These parts are so proportioned in order that the fluid may pass over the edge of the side A³ of the reservoir before it reaches the top of the developing-box A.

70 75 After the developing fluid has been poured out of the developing-box A and the reservoir A' water is introduced into said developing-box through the reservoir A and channel a in the same way that the developing fluid was previously introduced for the purpose of washing said plate, and finally after the developing-box A and reservoir A' have been emptied of water the fixing fluid is poured 80 85 into the said box in the same way through the reservoir and channel a.

What I claim is—

1. In a photographic developing apparatus, the combination of a developing-box adapted 90 to hold both the plate or film and the developing fluid, of a frame for transferring the plate or film from the plate-holder to the developing-box adapted to receive the plate or film from a plate-holder, and to discharge it 95 into the developing-box with the sensitized face of said plate uppermost, without exposing said plate to light; means for excluding light from said developing-box; and means for introducing developing fluid into said box 100 after the plate or film has been placed therein, without admitting light.

2. In a photographic developing apparatus, the combination with a developing-box adapted to hold both the plate or film and the developing fluid, of a reservoir adapted to hold developing fluid; a connection between said box and said reservoir; and a frame for transferring the plate or film from the plate-holder to the developing-box adapted to receive the 105 plate or film from a plate-holder, and to discharge it into the developing-box with the sensitized face of said plate uppermost, without exposing said plate to light; and means for excluding light from said developing-box. 110 115

3. In a photographic developing apparatus, the combination with a developing-box adapted to hold both the plate or film and developing fluid; of a light-proof frame for transferring the plate or film from the plate-holder to the developing-box adapted to contain such plate or film and to form a light-tight connection both with the developing-box and with the plate-holder; means for admitting the plate or film to said frame from said plate-holder 120 and for discharging it, face uppermost, into said developing-box, without exposing it to light; and means for introducing developing fluid into said box after the plate or film has been placed therein, without admitting light. 125 130

4. In a photographic developing apparatus, the combination with a developing-box adapted to hold both the plate or film and developing fluid; of a light-proof frame adapted to

contain the said plate or film, having one and the same side adapted to form a light-tight connection both with the developing-box and with the plate-holder, and having an opening 5 in said side to admit the plate or film; means for closing said opening light-tight; and means for introducing developing fluid into said box after the plate or film has been placed therein, without admitting light.

10 5. In a photographic developing apparatus, the combination with a developing-box adapted to hold both the plate or film and developing fluid, of a light-proof frame adapted to contain such plate or film, having one and the same side adapted to form a light-tight connection, both with the developing-box and with the plate-holder, an opening in said side to admit the plate or film; a slide to close such opening; and means for introducing developing fluid into said box after the plate or film has been placed therein without admitting light.

6. In a photographic developing apparatus the combination with a developing-box of 25 means for excluding light from said box; a reservoir adapted to hold developing fluid and having an opening for its introduction; overlapping shields in front of said opening that project into said reservoir from either 30 side alternately so as to form a tortuous passage from the opening to that part of the reservoir that contains the fluid; and a connection between said developing-box and said reservoir.

35 7. The photographic developing apparatus, comprising the developing-box A, and the reservoir A', with a connection between them for the passage of fluid; and the shields a^2 , a^3 , in the reservoir A', whose opposite sides are parallel, substantially as shown and described.

8. In a photographic developing apparatus, a frame for transferring the plate or film from a plate-holder to a developing-box, comprising a light-proof frame, having one and the same side adapted to make a light-tight connection both with the plate-holder and the developing-box, and an opening in such side through which the plate or film can be introduced into said frame from the plate-holder, and discharged therefrom into the developing-box, and means for closing such opening.

9. In a photographic developing apparatus, a frame for transferring the plate or film 5 from a plate-holder to a developing-box, comprising a light-proof frame, having one and the same side adapted to make a light-tight connection both with the plate-holder and the developing-box, and an opening in such

side through which the plate or film can be 60 introduced into said frame from the plate-holder, and discharged therefrom into the developing-box; means for closing such opening, and a non-actinic glass in its other side.

10. In a photographic developing apparatus, 65 a frame for transferring the plate or film from a plate-holder to a developing-box, comprising a light-proof frame, having one and the same side adapted to make a light-tight connection both with the plate-holder and the developing-box, and an opening in such side through which the plate or film can be introduced into said frame from the plate-holder, and discharged therefrom into the developing-box, means for closing such opening; 70 a non-actinic glass in the other side; and a removable cover for said glass.

11. The frame B having one and the same side adapted to fit light-tight both upon a plate-holder and upon a developing-box, having an opening in said side adapted for the passage of a plate or film therethrough, and having the slides B' , B^2 , septum B^4 , and non-actinic glass B^3 , substantially as shown and described.

12. In a photographic developing apparatus, the combination with the developing-box A, of the reservoir A'; a connection between said developing-box and reservoir through which fluid can pass; the frame B having one 90 of its sides adapted to fit light-tight upon the developing-box, and having an opening in said side for the passage of a plate or film, and the slide B' ; substantially as shown and described.

95 13. In a photographic developing apparatus, the combination with the developing-box A, of the reservoir A'; a connection between said developing-box and reservoir through which fluid can pass; the frame B having one 100 of its sides adapted to fit light-tight upon the developing-box, and having an opening in said side for the passage of a plate or film; the slides B' , B^2 ; and the non-actinic glass B^3 ; substantially as shown and described.

105 14. The combination with the developing-box A, of the reservoir A' separated from each other by the partition A^2 and connected therewith by the passage a ; shields a^3 , a^4 in the reservoir A'; the frame B adapted to fit light-tight the top of the developing-box A; the slides B' , B^2 , and the non-actinic glass B^3 ; substantially as shown and described.
